Patented April 26, 1904.

UNITED STATES PATENT OFFICE.

JACOB ROTHLISBERGER, OF NIAGARA FALLS, NEW YORK, ASSIGNOR TO ONEIDA COMMUNITY, LIMITED, OF KENWOOD, NEW YORK, A CORPORATION OF NEW YORK.

DESIGN FOR A HANDLE FOR SPOONS, FORKS, OR SIMILAR ARTICLES.

SPECIFICATION forming part of Design No. 36,892, dated April 26, 1904.

Application filed March 18, 1904. Serial No. 198,847. Term of patent 7 years.

To all whom it may concern:

Be it known that I, JACOB ROTHLISBERGER, a citizen of the United States, residing at Niagara Falls, county of Niagara, and State of New York, have invented a new, original, and ornamental Design for Handles for Spoons, Forks, or Similar Articles, of which the following is a specification, reference being had to the accompanying drawings, in which—

Figure 1 is the obverse side. Fig. 2 is the reverse side.

What I claim is—

The ornamental design for a handle for spoons, forks, or similar articles, as shown.

JACOB ROTHLISBERGER.
